Specification for Design.

Patented May 10, 1921.

Application filed September 21, 1918. Serial No. 255,192. Term of patent 14 years.

To all whom it may concern:

Be it known that I, CHARLES T. PFLUEGER, a citizen of the United States, residing at Akron, in the county of Summit and State of Ohio, have invented a new, original, and ornamental Design for the Surface Ornamentation of the Body of an Artificial Minnow Bait, of which the following is a specification, reference being had to the accompanying drawing, forming part thereof.

Figure 1 is a side elevation;
Fig. 2 is a top plan view; and,
Fig. 3 is a front end view.

I claim:

The ornamental design for surface ornamentation for the body of an artificial minnow bait, as shown.

CHARLES T. PFLUEGER.
